UNITED STATES PATENT OFFICE.

LOUIS BRAUER, OF PHILADELPHIA, PENNSYLVANIA.

IMPROVEMENT IN CAR-AXLE BOXES.

Specification forming part of Letters Patent No. **170,338**, dated November 23, 1875; application filed January 8, 1875.

To all whom it may concern:

Be it known that I, LOUIS BRAUER, of the city and county of Philadelphia and State of Pennsylvania, have invented a new and useful Improvement in Journal-Boxes; and I do hereby declare the following to be a clear and exact description of the nature thereof, sufficient to enable others skilled in the art to which my invention appertains to fully understand, make, and use the same, reference being had to the accompanying drawings, making part of this specification, in which—

Figure 1 is a front view of the interior of the device embodying my invention. Fig. 2 is a transverse vertical section thereof.

Similar letters of reference indicate corresponding parts in the two figures.

My invention consists in a frame secured within the box and interposed between the journal and the axis of the wheel in the box. It also consists in the wheel with a rotary axial pin and side depressions, in combination with a frame interposed between the journal and the axial pin, and having bearings set in the depressions.

Referring to the drawings, A represents the journal, and B the box thereof. Within the box there is suspended from the journal A a rotating ring or band, C, whose inner face at the part that is uppermost rests on the journal. D represents a wheel, which is arranged within the ring C, so as to be in contact with the inner face of the latter at the lowermost point thereof. The wheel D has its axle-pin E formed solid with the body thereof, and the sides of the wheel are cut away, or formed with spaces or depressions F. The bearings of the axis of

the wheel are brasses or boxes G, which are located in a frame, H, arranged within the box B, and bolted thereto without interfering with the motions of the band C. The frame H and brasses G occupy positions in the depressions F, so that they project but slightly, if any, beyond the sides of the wheel, and thus utilize space without decreasing the serviceable length of the axis E of the wheel.

It will be seen that the axis E formed with the wheel, and rotating therewith, is strong and durable, and able to stand the great strain transmitted from the journal. This construction also allows the use of brasses or removable boxes for the axis E.

The bearings, instead of being a frame bolted to the box B, may be passed through the sides of the box.

Having thus described my invention, what I claim as new, and desire to secure by Letters Patent, is—

1. The combination of axle-box, lubricating-wheel band, and supporting-frame, interposed between the journal A and axis of the wheel D, substantially as and for the purpose set forth.

2. The wheel D, with rotary axial pin E and side depressions F, in combination with the frame H, interposed between the journal A and the axial pin E, and with bearings set in the depressions F, substantially as and for the purpose set forth.

LOUIS BRAUER.
